UNITED STATES PATENT OFFICE.

HENRY E. ELROD, OF DALLAS, TEXAS.

INCINERATOR.

Application filed April 16, 1921. Serial No. 462,062.

To all whom it may concern:

Be it known that I, HENRY E. ELROD, a citizen of the United States, and a resident of Dallas, in the county of Dallas and State 5 of Texas, have invented certain new and useful Improvements in Incinerators, of which the following is a specification.

My invention relates to incinerators or furnaces adapted for burning garbage, and 10 refuse.

An object of my invention is to provide an incinerator which is of simple construction, can be cheaply and substantially built, one in which the simplicity of construction 15 is not detrimental to but on the other hand contributes to the efficiency of the furnace.

The structure in question is of particular design and comprises four walls with an arched top within which are contained a 20 fire grate, an inclined garbage grate and a horizontal platform disposed between the fuel grate and the garbage grate. In addition to the parts just mentioned there is provided an inclined table which assists in 25 forming a tortuous flue or passage-way for the smoke and gases, thereby conducting them in close proximity to the garbage, both over and under the garbage, whereby the full efficiency of the heat carried by the 30 smoke and gases may be utilized.

The arrangement of the parts is such that after the furnace has been started, no other fuel than that provided by the garbage and refuse need be used. The cost of operating 35 the incinerator is therefore reduced to a minimum, the device being extremely economical.

Because the construction of the device is such that the heated smoke and gases pass 40 over and under the garbage and refuse, thereby drying the wet garbage rapidly, an incinerator constructed in accordance with this invention will have a large capacity in tons of material incinerated per day.

45 The various features of construction and operation of my invention will be made more apparent in the accompanying specification and drawings in which:

Fig. 1 is a longitudinal section of an incinerator constructed in accordance with my 50 invention,

Fig. 2 is a transverse section taken on line 2—2 of Fig. 1 looking in the direction of the arrows,

Fig. 3 is a section on line 3—3 of Fig. 1 55 looking in the direction of the arrows, and, Fig. 4 is a horizontal section on line 4—4 of Fig. 1 looking in the direction of the arrows.

In the drawings the numeral 10 designates 60 a foundation made preferably of concrete from which front and rear walls 11 and 12 and side walls 13 respectively extend upwardly. The walls are formed preferably of brick and are connected by an arch 14. 65 This arch is preferably faced with fire brick 15 and between the fire brick and arch 14 suitable insulating brick or material 16 may be inserted.

Disposed at the top of the structure thus 70 far described there is provided a platform 17 formed preferably of concrete, this being in accordance with the practice in this art. For reinforcing and bracing the structure 75 vertically disposed I-beams 18 are provided disposed adjacent the sides 13, secured at the bottom by short tie-rods 19 projecting from the base 10 and at the top by transversely disposed tie-rods 20. Supports of a similar type 21 are provided adjacent 80 the front and rear walls and secured to the furnace body by tie-rods 22.

Adjacent the rear wall 12 of the furnace there is provided a smoke stack 23 which 85 may be lined with fire brick or suitable refractory material. This smoke stack communicates at its lower end with an opening 25 of the furnace and is provided with an opening and door 26 to enable soot and the like to be removed or to be taken therefrom. 90 The platform 17 is provided with a charging opening 27 suitably closed by a door 28. The charging opening 27 communicates with the interior of the furnace thereby enabling the refuse and garbage to be dumped into 95 the furnace at this point. The wall of the charging opening is formed of fire brick or other suitable refractory material 29 and faced on its bottom side with a metal plate 30 to facilitate the travel of the garbage and 100 refuse into the furnace.

In order to prevent the escape of heated smoke and odors from the combustion chamber during the charging of the garbage or refuse through the charging opening 27, I 105 provide a swinging door 31 formed hollow in order to permit water to be supplied thereto. The door is pivoted at its upper

end upon suitable hollow trunnions 32, to which trunnions are connected a pipe 33, extending transversely of the furnace. Water is supplied to the door 31 through the 5 pipe 33, which pipe terminates at one of the trunnions and steam generated by the heat in the combustion chamber may escape through a similarly disposed pipe 34. This swinging door 31 is opened by pressure of 10 the garbage or refuse in the charging opening 27 and closes by gravity when the charging operation is completed. If desired, suitable mechanical devices, such as gears and levers may be employed for positively 15 operating the swinging door 31.

At the front of the furnace there are provided a set of fire grates 35 disposed over ashpits 36 between the side walls 13. Suitable fire box and ashpit doors 37 and 38 respectively are provided whereby access may 20 be had to the fire grates and ashpits.

Extending longitudinally of the furnace and centrally disposed is an inclined grate 39. The forward end of the grate 39 is supported by a retaining wall 40 which is of sufficient width to provide a horizontal platform 41. The platform 41 is so disposed as to lie at the base of the inclined grate 39 and between this grate and the fire grates 30 35, for a purpose to be more fully herein-after described. If desired, the wall 40 may be provided with a transversely extending passage way 42 closed by doors 43 at the sides of the furnace. The retaining 35 wall 40 and platform 41 are formed preferably of fire brick or other refractory material.

The rear end of the grate 39 is supported upon a retaining wall 44 extending transversely of the furnace. This wall 44 forms with one side of a passage way 45 closed at its ends by doors 45'. The wall 44 is provided with a centrally disposed opening 46 preferably arched as illustrated. The rear 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 at the side of the furnace. These doors permit access to the furnace at this point to enable matter to be removed should the occasion arise. Also disposed at this point is a suitable sump 53 for the purpose of gathering liquid from the garbage or refuse which has not been evaporated. The heated gases which continually pass over the sump will tend to evaporate any liquid gathered there. As illustrated in Fig. 1 suitable sewerage connection 54 may be provided for carrying off any liquid not evaporated.

Disposed parallel with the rear wall 12 is a passage way 55 closed by suitable doors 56 at the sides of the furnace. This permits ashes or the like to be raked out of the passage way leading to the smoke stack.

The arrangement of the parts is such that smoke and heated gases are directed by the arched roof in the directions indicated by the line of arrows 57 and around the charging opening 27. Then through the opening 46 in the wall 44 passing under the grate 39 and over the table 48. Then over the sump 53 through opening 49 and under the table 48 through opening 25 to the smoke stack 23.

In operation the furnace works as follows:

The fire is built upon the grates 35, fuel being introduced through fire door 37. A draft will be created by the stack 25. When the combustion chamber is thoroughly heated the cover 28 of the charging opening is removed and garbage and refuse admitted into this charging opening. The force of the garbage against the swinging door 31 will force the same open and permit the garbage to move on to the grate 39. Wet garbage will percolate through the bars of the grate 39 and fall on to the inclined table 48, thus facilitating the drying out and burning of the garbage and refuse retained on the grate 39. As hereinbefore stated, heat from the fire on grates 35 is directed over the grate 39 around through passage way 45 and opening 46 so that it passes under the grate 39 and over table 48. This circulation of the heated smoke and gases passing over the refuse on grate 39 and over the liquid on the table 48 will quickly consume and evaporate much of the said refuse and liquids.

After the furnace has been set in operation the garbage and refuse contained on the grate 39 will be raked down onto fire grates 35 so that no other fuel need be supplied to the fire grates. In reality, if a sufficient amount of garbage and refuse is supplied to the grate 39 it will tend to work its way downwardly and fall on the fire grates 35. This occurs because of the inclined position of the grate 39. The feeding of the refuse from the grate 39 to the grates 35 is controlled by the platform 41,

the front edge of the table 48 is a passage way 50 between the table 48 and the base of the furnace. The passage way 50 communicates with the opening 25 leading to the smoke stack 23. Disposed transversely of the furnace and immediately below the front edge of the table 48 is a passage way 51 closed by suitable doors 52

disposed at the base of the inclined grate 39. Because this platform is horizontally arranged, the feeding action will be retarded and the refuse and garbage caused ⁵ to remain for a longer period upon the inclined grate 39. This insures a more thorough drying out of the wet refuse and garbage, thereby facilitating its burning when it falls upon the fire grates 35.

10 The heated gases and smoke keep the inclined table 48 in a higher heated condition whereby the liquid which percolates through the grate 39 will to a great extent, be evaporated. However, that portion of 15 the liquid which is not evaporated upon the table 48 will fall onto the sump 53 and part of this will then be evaporated because heated gases are constantly passed over this sump. The remaining liquid 20 which is usually of a negligible quantity may be carried off by the sewerage connection 54.

Sufficient heat is generated in the furnace to consume all smoke and odors created 25 through the combustion of the garbage and refuse so that the operation of the incinerator is odorless and unobjectionable.

By disposing the fire grates at one end of the structure and the smoke stack which 30 creates the draft at the other end, the heated gases and smoke are efficiently utilized. Extending from the fire grates is the arched roof which will direct the heated smoke and gases rearwardly and over the 35 refuse contained on the inclined grate 39. This heated smoke and gases are thereafter conducted through the passage way 45 and directed under the grate and over the table 48 by reason of the disposition of the opening 40 46. Hence the refuse on the grate 39 is subjected to the heat of the smoke and gases on its bottom while the wet garbage on the table 48 is also subjected to the heat of the smoke and gases. It will be further 45 noted that the smoke and gases is then conducted under the table 48 whereby any remaining heat will be utilized in keeping the table 48 heated. The gas is thereafter passed from the opening 25 to the smoke 50 stack 23 and is discharged at the top thereof.

The door 31 which is subjected directly to the heat of the combustion chamber is cooled by the circulation of water there- 55 through. By the inter-position of this door the charging of the furnace is facilitated inasmuch as the obnoxious gases resulting from the combustion of the garbage and refuse are to a great extent prevented from escap- 60 ing through to the charging opening 27.

While the structure illustrated in these drawings and described in the foregoing specification has proved to be an efficient one, I do not wish to be limited in the man- 65 ner of details but reserve the right to make

such changes and modifications as become necessary and come within the purview of the accompanying claims.

Having thus described my invention, what I claim is:

1. An incinerator of the class described comprising a combustion chamber having a base and front, back and side walls rising from said base, an arch connecting said walls and extending from the front to the rear of said combustion chamber, said combustion chamber being provided with an opening whereby garbage may be introduced therein, fire grates disposed at the front of said combustion chamber, an inclined grate disposed centrally of said combustion chamber and adjacent said fire grates, an inclined table disposed beneath said inclined grate, a smoke stack and a passageway connecting said stack with said combustion chamber, said passageway extending over and under said table and thence to said smoke stack.

2. An incinerator comprising a combustion chamber having a base and front, back and side walls rising from said base with an arched roof connecting said walls, said arched roof extending from the front side of said combustion chamber upwardly and toward the back wall thereof, said combustion chamber being provided with a charging opening whereby garbage may be introduced into said chamber, a pivoted door disposed in said discharge opening, means for cooling said door, a pair of fire grates disposed adjacent the front wall of said combustion chamber, an inclined grate disposed centrally of said combustion chamber, said inclined grate being inclined rearwardly and upwardly, an inclined table disposed beneath said inclined grate, a smoke stack and means providing communication between said combustion chamber and said smoke stack whereby the smoke and combustion gases are conducted over and under said inclined grate, substantially as and for the purpose described.

3. A garbage burning furnace comprising a combustion chamber having a front, back and side walls rising from said base together with an arched roof connecting said walls, said arched roof extending from the front wall and being inclined upwardly toward the rear wall, said arched roof being provided with a charging opening whereby garbage may be introduced into the combustion chamber, fire grates disposed adjacent the front wall, a retaining wall adjacent said fire grates forming a horizontally disposed platform, a retaining wall arranged adjacent the back wall of said combustion chamber, an inclined grate supported upon said retaining walls, said grate being inclined upwardly and rearwardly of the combustion chamber, an inclined table disposed

beneath said inclined grate, said second mentioned retaining wall being provided with an opening disposed beneath said inclined grate, said inclined table being formed so as to provide a passage way beneath the same, a smoke stack and a passage way connecting said smoke stack with the passage way provided under said inclined table, whereby the smoke and gases from the combustion chamber will pass out through said stack, as and for the purpose described.

4. A garbage burning furnace comprising a combustion chamber having a front, back and side walls rising from said base together with an arched roof connecting said walls, said arched roof extending from the front wall and being inclined upwardly toward the rear wall, said arched roof being provided adjacent the back wall of the combustion chamber with a charging opening, a cover for said charging opening and a swinging door disposed within said charging opening, fire grates arranged adjacent the front of said combustion chamber, an upwardly and rearwardly inclined grate disposed centrally of said combustion chamber, a retaining wall for supporting the forward end of said inclined grate, said retaining wall being disposed so as to form a horizontally arranged platform, a retaining wall disposed transversely of said combustion chamber and supporting the rear edge of said inclined grate, said retaining wall forming with the back wall of said combustion chamber a transversely disposed passage way, said retaining wall being provided with an opening disposed under said inclined grate, an inclined table projecting from said retaining wall and inclined similarly to said grate, said inclined table being arranged so as to provide a passageway beneath the same, said inclined table being arranged so as to provide communication between its upper and lower sides, a smoke stack arranged against the rear wall of said combustion chamber, a passage way connecting said smoke stack to the passage way disposed under said inclined table whereby the heated smoke from said fire grates will be directed rearwardly from said inclined grate, through said transverse passage way, between said inclined grate and inclined table, under said inclined table to said smoke stack, substantially as and for the purpose described.

5. A garbage burning furnace comprising a combustion chamber having a front, back and side walls rising from said base together with an arched roof connecting said walls, said arched roof extending from the front wall and being inclined upwardly toward the rear wall, a platform over said arched roof, said arched roof being provided adjacent the back wall of said combustion

chamber with a charging opening, a cover for said opening, a door pivotally mounted adjacent its upper edges disposed in said charging opening, a set of fire grates disposed transversely of said combustion chamber adjacent the front wall thereof, an inclined grate disposed centrally of said combustion chamber and inclining rearwardly and upwardly, the rear edge of said inclined grate being disposed immediately adjacent said charging opening, a platform disposed adjacent said fire grates, said platform supporting the forward edge of said inclined grate, a retaining wall disposed transversely of said combustion chamber and under said charging opening, said retaining wall supporting the rear end of said inclined grate, said retaining wall forming one side of a transversely disposed passage way, the ends of said passage way being in communication with said combustion chamber, said retaining wall being provided with a centrally disposed opening, a forwardly and downwardly inclined table projecting from said rear wall and immediately adjacent said passage way, said table stopping short of said platform, the under side of said table being arched to form a passage way thereunder and to permit communication between the upper and under sides of said table, a transversely disposed passage way immediately adjacent the forward edge of said table, doors for closing the ends of said passage way, a sump formed in the base of said combustion chamber and under the forward edge of said inclined table, a smoke stack and means providing communication between said smoke stack and the passage way of said inclined table, whereby smoke and heated gases from said fire grates will pass over and under said inclined grate and thereafter under said inclined table to be discharged through said smoke stack.

6. A garbage burning furnace comprising a combustion chamber having a front, back and side walls rising from said base together with an arched roof connecting said walls, said arched roof extending from the front wall and being inclined upwardly toward the rear wall, said arched roof being provided with a charging opening, a metal plate forming the bottom and the side of said charging opening, a cover plate for said opening, a gravity closed door inserted in said opening, means for supplying a cooling fluid to said door, fire grates disposed transversely of said combustion chamber adjacent the front wall and near the base thereof, ash-pits formed beneath said fire grates, fire and ashpit doors for said grates and ashpits, a transversely disposed platform immediately adjacent said fire grates, a transversely disposed retaining wall at the rear of said combustion chamber and spaced from the rear wall thereof, an inclined garbage grate sup-

ported by said platform and retaining wall, the rear end of said inclined grate being disposed adjacent the inner end of said charging opening, whereby garbage introduced into said charging opening will be directed upon said inclined grate, said retaining wall forming with the rear wall of the combustion chamber a transversely disposed passage way, said passage way being in communication with said combustion chamber adjacent the ends of the passage way, said retaining wall being apertured centrally thereof in order to provide communication between said passage way and the under side of said inclined grate, and inwardly and downwardly inclined table commencing at said passage way and extending to a point short of said platform, said inclined table being spaced from said inclined grate to provide 20 a passage way between, said inclined table being formed with a passage way beneath the same, said passage way opening so as to be in communication with the passage way formed by the upper side of said table, a sump formed in said base adjacent the forward edge of said inclined table, a smoke stack disposed adjacent the rear wall of said combustion chamber, said smoke stack communicating with the passage way provided under said inclined table, whereby the heated 25 combustion gases from said fire grates will be directed rearwardly by said arched roof over said platform and inclined grate, into said transversely disposed passage way, through said opening and between said inclined grate and inclined table and under said inclined table to said smoke stack where it is discharged, substantially as and for the purpose described.

HENRY E. ELROD.
